F. P. ZWICKER.

ERASING SHIELD.

APPLICATION FILED OCT. 27, 1919.

Patented Sept. 14, 1920.

FIG. 1.

FIG. 2.

INVENTOR
FREDERICK P. ZWICKER

BY *Thompson Townsend*
ATTORNEYS

UNITED STATES PATENT OFFICE.

FREDERICK P. ZWICKER, OF SAN FRANCISCO, CALIFORNIA, ASSIGNOR OF TWENTY-FIVE PER CENT. TO WILBUR J. RYAN AND TWENTY-FIVE PER CENT. TO ALBERT H. HOLADAY, BOTH OF SAN FRANCISCO, CALIFORNIA.

ERASING-SHIELD.

1,353,133.

Specification of Letters Patent. Patented Sept. 14, 1920.

Application filed October 27, 1919. Serial No. 333,669.

To all whom it may concern:

Be it known that I, FREDERICK P. ZWICKER, a citizen of the United States, residing at the city and county of San Francisco and State of California, have invented new and useful Improvement in Erasing-Shields, of which the following is a specification.

This invention relates to an erasing shield for typewriting machines and the like.

One of the objects of the present invention is to provide a simple and cheaply manufactured erasing shield for typewriting machines which may be easily and readily placed on the platen cylinder and inserted between the sheets of the paper and the carbons, whereby erasures may be neatly made on each sheet without smearing or blurring the other copies.

Another object of the invention is to provide supporting members at each end of the shield so as to slightly elevate it with relation to the platen and the underlying sheets, thereby protecting the surface and sheets below the point of erasure from the pressure caused by such erasure.

Another object of the invention is to provide means for rigidly securing the shield against movement with relation to the sheets or the platen when in use.

Further objects will hereinafter appear. The invention consists of the parts and the construction, combination and arrangement of parts as hereinafter more fully described and claimed, having reference to the accompanying drawings, in which—

Figure 1 is a perspective view of the erasing shield.

Fig. 2 is a partial side elevation of a typewriter, showing the position of the shield on the platen when in use.

Referring to the drawings in detail, A indicates in general the frame of the typewriter; 2, the platen; and 3, the keys.

The erasing shield forming the subject matter of the present invention is generally shown in Fig. 1. It consists of a curved, shield-like member B which is adapted to extend substantially from end to end of the platen, the curvature of the shield being substantially the same as the contour of the platen. Formed at each end of the shield B are downwardly projecting supporting members 3, and formed on each supporting

member are serrations or teeth 4 which are adapted to engage the surface of the platen in such a manner as to rigidly secure it against movement with relation to the platen or the sheets when erasures are being made thereon. The shield is otherwise provided with a handle 5 projecting substantially at right angles thereto, to permit the shield to be readily handled and held when in use. The supporting members 3 formed at the ends of the shield are provided for the purpose of slightly elevating the shield with relation to the platen and any sheets or carbons that may underlie the shield. The pressure exerted on the shield when an erasure is being made thereon will therefore not be exerted upon any underlying sheets and smudges or blurring is therefore eliminated.

The shield is in actual practice sufficiently long to extend approximately from end to end of the cylindrical platen and as the supporting extensions or elevating members 3 are comparatively short, it can readily be seen that the typewritten sheets and the carbons interposed between the same will lie between the supporting members. The serrations 4 formed on said members will therefore not perforate any of the sheets as they engage that portion of the platen which extends beyond the sheets.

In actual practice if a mistake is made, it is only necessary to turn up the first sheet, as indicated at 6. The shield is then grasped by the handle 5 and placed in the position shown in Fig. 2, where it will underlie sheet 6 and overlie the remaining carbons and copies; the line to be erased should, however, preferably be turned up a couple of spaces to permit the section being erased to be readily reached. Each successive sheet or copy may thus be erased and corrected without exerting pressure on the underlying sheets. Blurring of the lines or smudges are thus eliminated and neat and clean work is the result.

The shield shown is in this instance constructed of a single piece of sheet metal, the handle 5 and the supporting members 3 being bent into their respective places from said sheet and the main supporting surface B being bent to conform to the outer contour of the cylindrical platen.

I wish it understood that while it is here shown as an integral construction, it is obvious that various changes in design and proportions may be resorted to within the scope 5 of the appended claims; similarly, that the materials and finish of the several parts may be such as the experience and judgment of the manufacturer may dictate.

Having thus described my invention, 10 what I claim and desire to secure by Letters Patent is—

1. An erasing shield for typewriting machines comprising a curved shield, and supporting members at each end of the shield 15 adapted to rest upon the platen of the typewriting machine and to slightly elevate the shield with relation to the platen.

2. An erasing shield for typewriting machines comprising a curved shield adapted 20 to extend substantially from end to end of the platen cylinder on the machine, and means at each end of the shield adapted to engage the platen of the typewriting machine and to slightly elevate the same with 25 relation to said platen.

3. An erasing shield for typewriting machines comprising a curved shield adapted to extend substantially from end to end of the platen cylinder on the machine, and 30 downwardly projecting supporting members at each end of the shield, adapted to rest upon the platen near the ends thereof

and to slightly elevate the shield with relation to the platen.

4. An erasing shield for typewriting machines comprising a curved shield adapted 35 to extend substantially from end to end of the platen cylinder on the machine, downwardly projecting supporting members at each end of the shield, adapted to slightly 40 elevate it with relation to the platen, and serrations formed on each supporting member to secure the shield against movement with relation to the platen when in use.

5. An erasing shield for typewriting machines comprising a curved shield adapted 45 to extend substantially from end to end of the platen cylinder on the machine, downwardly projecting supporting members at each end of the shield, adapted to slightly 50 elevate it with relation to the platen, serrations formed on each supporting member to secure the shield against movement with relation to the platen when in use, and a handle on the shield to permit it to be applied or removed with relation to the platen.

In testimony whereof I have hereunto set my hand in the presence of two subscribing witnesses.

FREDERICK P. ZWICKER.
